Specification for Design.

Patented Aug. 5, 1913.

Application filed May 5, 1913. Serial No. 765,691. Term of patent 14 years.

To all whom it may concern:

Be it known that I, EUGENE S. NEWBOLD, a citizen of the United States, residing at 831 Greenmount avenue, in the city of Baltimore, and State of Maryland, have invented a new, original, and ornamental Design for Street-Lamps, of which the following is a specification, reference being had to the accompanying drawing, forming part thereof.

Figures 1 and 2 are respectively, two side views of a street lamp, taken in directions at

right angles to each other and showing my new design.

I claim:

The ornamental design for a street lamp, as shown.

The foregoing specification signed at Baltimore, Md., this 14th day of March, 1913.

EUGENE S. NEWBOLD.
